US0D1056851S

(12) **United States Design Patent** (10) **Patent No.:** **US D1,056,851 S**
(45) **Date of Patent:** **** Jan. 7, 2025**

(54) **HOUSING FOR A POWER DISTRIBUTION MODULE**

(71) Applicant: **REDARC TECHNOLOGIES PTY LTD**, Morphett Vale (AU)

(72) Inventors: **Alec Bryce**, St Clair (AU); **Mitchell Geci**, Reynella East (AU); **Albert Atkins**, Hectorville (AU)

(73) Assignee: **Redarc Technologies Pty Ltd.** (AU)

(**) Term: **15 Years**

(21) Appl. No.: **29/865,681**

(22) Filed: **Aug. 8, 2022**

(30) **Foreign Application Priority Data**

Feb. 10, 2022 (AU) 202210769

(51) **LOC (15) Cl.** **13-03**

(52) **U.S. Cl.**

USPC **D13/133**

(57) **CLAIM**

The ornamental design for a housing for a power distribution module, as shown and described.

DESCRIPTION

FIG. 1 is a top view of a housing for a power distribution module;

FIG. 2 is a bottom view thereof;

FIG. 3 is a front side view thereof;

FIG. 4 is a rear side view thereof;

FIG. 5 is a left side view thereof;

FIG. 6 is a right side view thereof;

FIG. 7 is a top, rear side, perspective view thereof; and,

FIG. 8 is a top, front side, perspective view thereof.

The broken lines shown in the drawings illustrate portions of the housing that form no part of the claimed design.

1 Claim, 8 Drawing Sheets
